LAVATORY BOWL

Perry F. Stromblad, Clairton, Pa.

Application August 14, 1940, Serial No. 352,624

2 Claims. (Cl. 4—254)

This invention relates to new and useful improvements in lavatory equipment and more particularly to a lavatory bowl.

The principal object of the present invention is to provide a foot rest for use in conjunction with lavatory bowls and which may form part of the construction of a lavatory bowl, for the purpose of permitting the occupant to have his knees elevated and in a more natural position.

Another important object of the invention is to provide a foot rest for lavatory bowls which can be adjusted as requirements demand.

Other objects and advantages of the invention will become apparent to the reader of the following specification.

In the drawings:

Figure 1 represents a side elevational view of the bowl and foot rest.

Figure 2 is a section on the line 2—2 of Figure 1.

Figure 3 is a fragmentary enlarged detailed sectional view taken substantially on the line 3—3 of Figure 1.

Figure 4 is a front elevational view of the rest.

Figure 5 is a side elevational view of a lavatory and rest somewhat modified over that shown in Figure 1.

Figure 6 is a side elevational view of a lavatory and rest of still another form.

Figure 7 is an edge elevational view of a bridge member which may be used with any one of the forms of the invention.

Referring to the drawings wherein like numerals designate like parts, it can be seen that numeral 5 represents the lavatory bowl having the seat 6 and cover 7. Numeral 8 denotes the usual flush tank.

In carrying out the present invention, numeral 9 generally refers to the foot rest which as shown in Figure 4 consists of the pair of vertical posts 10—10 having feet or the like 11 at the lower ends thereof for rest upon the floor 12. Three-way elbows 13 connect the upper ends of the legs 10 with the rearwardly disposed elongated rails 14 and the front horizontal rail 15.

In the form of the invention shown in Figure 1, the lavatory 5 is constructed with a bored boss or protuberance 16 on each side thereof into which the rear end portions of the rails 14 are disposed. The rear ends of the rails 14 are provided with heads 17 for snug sliding disposition in the cylindrical bores of the bosses 16. One end of each of the bosses 16 is closed while the other end is provided with a removable cap 17a which when detached from the corresponding bores permit removal of the head 17 from the bore. Obviously, the rest can be moved inwardly or outwardly with respect to the bowl to suit the comfort of the lavatory user.

Another form of the invention is shown in Figure 5 wherein numeral 16a denotes a cylindrical boss on the side of the bowl 5a which has a bore therethrough. The stand is constructed in accordance with the stand 9 and has the horizontal rails 14a which extend into the bosses 16a. The end of each of the bosses 16a through which the rails 14a extend has a bore smaller than a main bore through the same to the end that a shoulder will be formed against which a spherical-shaped head 17a can abut when the stand is pulled forwardly to prevent complete detachment of the stand from the bosses.

Still another form of the invention is shown in Figure 6, wherein a stand is provided having the corner posts 10a and the rearwardly extending rails 14', the latter extending through T-fittings at the upper ends of legs 20 connected by bases 21 to the floor 12. The rails 14' are provided with heads 19' at the rear ends thereof to serve as stops in complement with the T-fittings 22.

A bridge member 23 provided with spring clips 25 for engagement with the rails 14, 14a or 14' can be employed for bridging the said rails.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In combination with a lavatory bowl, a pair of horizontally disposed guides, one at each side of the bowl, a pair of horizontally extending members each having one end disposed into a corresponding guide, a foot supporting member bridging the horizontally disposed members, and leg members for the forward ends of the horizontally disposed members, said guides each consisting of a barrel mounted on a corresponding side of the bowl.

2. In combination with a lavatory bowl, a pair of horizontally disposed guide barrels, one at each side of the bowl, a pair of horizontally extending members each having one end disposed into a corresponding guide barrel, said horizontally extending members terminating in front of the bowl, a horizontal member connecting the forward ends of the horizontally extending members, leg members for the forward ends of the horizontally disposed members, each of the horizontally extending members being provided with their heads for slidably disposition in the corresponding barrel, each of said barrels having a closed end and a removable cap at its opposite end.
